UNITED STATES PATENT OFFICE.

JACOB B. BEAM AND GEORGE W. BEAM, OF BIG RUN, PENNSYLVANIA.

DOOR-SILL.

SPECIFICATION forming part of Letters Patent No. 365,774, dated July 5, 1887.

Application filed January 29, 1887. Serial No. 225,871. (No model.)

To all whom it may concern:

Be it known that we, JACOB B. BEAM and GEORGE W. BEAM, both of Big Run, Jefferson county, Pennsylvania, have jointly invented certain new and useful Improvements in Door-Sills, of which the following is a specification.

The object of our invention is to provide an improved arrangement whereby a weather-tight joint is afforded at the bottom of the door, and also to provide a removable door-sill of convenient and economical structure.

In the accompanying drawings, Figure 1 is a view of the exterior of the door and its frame; Fig. 2, a vertical section on the line 2 2 of Fig. 1, and Fig. 3 a horizontal section on the line 3 3 of Fig. 2.

A represents an ordinary door-frame, B the sub-sill, and C the side strips against which the door closes. The removable sill D is preferably formed of metal, and is cast or wrought so as to be of the arched cross-section shown in Fig. 2. It slides between the sides of the door-frame, and is retained in place by sliding bolts d, which shoot into the frame. These bolts are preferably arranged, as shown, in the hollow on the under side of the sill, and are thrust back and forth by means of studs or handles l, which project through slots f in the sill. A longitudinal depression, preferably having a cross-section represented by the quadrant of a circle, (see Fig. 2), is formed in the upper face of the sill. A rocking weather-strip, E, is pivoted by means of short journal-studs formed on its ends in the end walls, d', of the longitudinal depression or recess. At one of these bearing-studs the weather-strip E is bent away, as shown, and a coiled spring, F, is disposed around it, one end being fastened to the sill and the other bearing upon the under side of the strip. The normal tendency of this spring is to throw the weather-strip up vertically against the outer face of the lower edge of the door, as seen in Fig. 1; but this can only take place when the door is closed, because of an extension, x, at one end of the strip, which is of such length that the door, even when in its most open position, cannot pass off from it. The weather-strip is therefore held horizontal and flush with the sill when the door is open. We preferably form the

sill at this end with an extension, y, which overlaps the door-frame and lies in a recess in the face of the frame, or under the edge of a strip, z, which may be secured on the frame. 55 When the door is open, the weather-strip E is horizontal and lies perfectly flush with the upper face of the sill; but when the door is closed the strip is automatically thrown up vertically against its face, so as to form a 60 closed joint. With this construction there is no obstruction or irregularity upon the face of the sill, as we dispense entirely with the ordinary lugs or fingers which have heretofore been generally used in devices of this class. 65 Apertures o, leading from the bottom of the recess in the sill to the outside of sill, may be provided to draw off any water that may find its way into the recess.

The construction shown in the drawings is a 70 practical one; but we do not limit ourselves specifically to the identical details shown.

We are aware that heretofore a weather-strip somewhat similar in construction to that illustrated has been thrown up against the 75 outer face of the door by a lug or finger on the sill, located so as to be struck by the door when closed. We are also aware that heretofore it has been proposed to form a closed joint between the bottom of a door and the sill by 80 means of a hinged strip which is pressed up against the under edge of the door by a spring. We do not, therefore, claim any such subjects-matter.

We are aware of the patents of Moore and 85 Whitney, No. 155,807; Brown and Brownell, No. 126,014, and Kintner, No. 313,742, and do not claim any subject-matter shown therein; but

What we claim as our invention is— 90

1. An arched metallic door-sill provided with retaining-bolts at its ends adapted to shoot into the door-jamb for holding the sill in place, and having a recess in its upper face, in combination with a flat weather-strip pivoted in the end walls of the recess and adapted to lie horizontally flush with the sill when the door is open and to be turned up into a vertical position against the side of the door when closed, substantially as and for the purpose 100 set forth.

2. The combination of a door-sill formed

with a recess in its upper face, having slots *f*, a weather-strip pivoted in the end walls of the recess, the retaining-bolts, one in each end of the door-sill, which are adapted to shoot into the door-jamb, and the studs or handles on the bolts, which project through slots in the sill below the weather-strip, substantially as and for the purpose set forth.

3. The combination of a door-sill formed with a longitudinal recess or depression in its upper face, a weather-strip pivoted at its ends in the upper part of the recess and which lies horizontally flush with the sill when the door is open, and a spring which throws the weather-strip up into a vertical position parallel with and against the side of the door when the door is closed, substantially as set forth.

4. The combination of a door-sill having a depression in its upper face, a pivoted weather-strip, the spring which throws the weather-strip up against the face of the lower edge of the door when the door is closed, and the extension of the weather-strip, by means of which the strip is held horizontally flush with the sill when the door is in its most open position.

In testimony whereof we have hereunto subscribed our names.

JACOB B. BEAM.
GEORGE W. BEAM.
